UNITED STATES PATENT OFFICE.

HENRY W. KAKASKA, OF MANDAN, NORTH DAKOTA.

SPARK-PLUG INTENSIFIER.

1,271,037.

Specification of Letters Patent. Patented July 2, 1918.

Application filed May 8, 1917. Serial No. 167,229.

To all whom it may concern:

Be it known that I, HENRY W. KAKASKA, a citizen of the United States, residing at Mandan, in the county of Morton and State of North Dakota, have invented a new and useful Spark-Plug Intensifier, of which the following is a specification.

The present invention relates to a spark plug attachment or intensifier, and aims 10 to provide a device of that character adapted especially for use upon old or sooted spark plugs to renew the life and efficiency thereof.

A further object of the invention is the 15 provision of a spark plug intensifier of extremely simple and inexpensive construction, which can be cheaply manufactured, and which will serve its office in a thoroughly practical and efficacious manner.

20 With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed, without departing from the spirit of the invention.

30 The invention is illustrated in the accompanying drawing, wherein:—

Figure 1 a side elevation of the attachment as applied to a spark plug.

35 Fig. 2 is a plan view of the device.

In carrying out the invention, there is provided an elongated strip or plate 1 of fiber or other suitable insulating material having engaged therethrough near one end, 40 a bolt 2 fastened to the plate by means of a nut 3 thereon, and bearing a binding nut 4 to clamp the terminal of the conductor 5. The conductor is applied to the binding post provided by the bolt 2 and nuts thereon, instead of being attached to the spark plug.

A metallic strip 6 is riveted between its ends, as at 7, to the plate 1 near the other end thereof, and has a protruding flat flush 50 terminal 8 to be clamped to the spark plug 10 in the manner of an ordinary conductor,

the terminal 8 being slotted, as at 9, to fit astride the binding post or central conductor of the spark plug. The inner terminal 11 of the strip 6 is preferably tapered, and bent at an acute angle from plate 1 and is spaced slightly from the binding post to provide a spark gap, whereby the device will serve its office of an intensifier, to renew the life of the plug. The strip 6 is attached to and support 1 by the plug, while the plate 1 is supported from the strip 6, the binding post being in turn supported by the plate. This provides an extremely simple, yet sufficient device for the intended purposes. The terminal 11 being spaced from the binding post, provides a spark gap which will intensify the sparks produced by the plug.

The device above described embodies, briefly considered, a spark plug 10 having a binding member 50 thereon, and a metal strip 6 having a flat end 8 the opposite faces of which are engaged directly by the plug 10 and by the binding member 50 to afford an increased contact. An insulating plate 1 is overlapped on the strip 6, a securing device 7 uniting the plate and the strip. A binding post 2 is carried by the outer end of the plate 1, the outer end 11 of the strip 6 being disposed at an acute angle to the plate 1 to point toward the post 2. The plate 1 terminates, as shown at 51, at the periphery of the post 10 and bears thereagainst, to prevent a swinging of the plate 1 on the securing device 7 and to prevent a shifting of the outer end 11 of the strip 6 with respect to the post 2, should the securing device 7 loosen its hold.

Having thus described the invention, what is claimed as new is:—

The combination with a spark plug having a binding member thereon, of a metal strip having a flat end the opposite faces of which are engaged directly by the plug and by the binding member to afford an increased contact; an insulated plate overlapped upon the strip; a securing device uniting the plate and the strip; and a binding post carried by the outer end of the plate, the outer end of the strip being disposed at an acute angle to the plate to point

toward the post, the plate terminating at the periphery of the post and bearing thereagainst to prevent a swinging of the plate upon the securing device and a circumferential shifting of the outer end of the strip with respect to the post should the securing device loosen its hold.

In testimony that I claim the foregoing as my own I have hereto affixed my signature in the presence of two witnesses.

HENRY W. KAKASKA.
